WALTER J. CARROLL, OF DETROIT, MICHIGAN.

CORK COVER OR SHIELD.

Application filed December 3, 1924. Serial No. 753,677.

My invention relates to covers or shields to be secured to the large ends of corks of bottles or other containers, for convenience and cleanliness in removing and handling the corks.

The object of my invention is to provide a light weight inexpensive cork cover or shield which can be securely attached directly to the cork, the design of the shield making it impossible for any of the liquid which may adhere to the cork to stain or injure the fingers in handling, or the surface of a desk or table on which it may be placed.

15 My invention is shown in the accompanying sheet of drawings, in which:—

Figure 1 is a side elevation showing the device in place on a bottle. Figure 2 is a vertical cross section view through the center. Figure 3 is a view of the device showing the position it assumes when placed on its side on the surface of a desk or table.

Similar reference characters refer to similar parts in each of the views.

25 The shield proper is formed from thin sheet metal such as tin, brass, aluminum, or other desired material which can be cut and formed with dies. It comprises three sections, a handle or knob, a neck and a skirt.

30 A knurled knob 6 is formed on its upper end for convenience in handling and also provides a recess for holding the large end of the cork 5. A neck 7, which serves to hold the cork 5 in position as shown in Figure 2,

35 is crimped or knurled so as to hold the cork securely against being pulled out or rotated. The hole 10 in the top of the knob is provided so that tightly fitting corks may be removed by means of an ordinary cork-

40 screw without danger of pulling the shield from the cork. The lower part or skirt 8 of the shield is larger in diameter than the neck of the bottle and extends a short distance below the bottom of the cork 5 so

45 that the lower end of the cork cannot come in contact with any surface on which the shield may be placed in a vertical position.

However, the usual manner of placing the device when removed from a bottle is to lay it on its side when it will at once assume and

retain the position shown in Figure 3, owing to the center of gravity being located above the skirt 8 of the shield. In this position any liquid which may be adhering to the cork 5 will run down or drop into the skirt 8 of the shield. In order that this liquid may be prevented from running or dropping out when the shield is raised to a vertical position in replacing the cork in the bottle, an inner groove 9 is formed from and integral with the lower edge of the skirt 8, being of sufficient diameter internally to pass freely over the enlarged top of the neck of the bottle, and of sufficient capacity to hold the excess liquid until it has evaporated. This construction will entirely prevent any of the liquid which usually adheres to the cork from soiling either the surface upon which it may be placed or the fingers of the person handling it.

55 The internal diameter of the inner groove 9 must be enough greater than the external diameter of the neck of the bottle in order that the cork may be inserted tightly within the neck as freely and securely as a cork unprovided with a shield. Usually the increased diameter necessary for the shield to pass freely over the enlarged top of the bottle's neck will assure ample spacing of the inner groove from contact with the neck. 60

65 It will be evident that in the manufacture of the device the cork 5 may be placed within the neck 7 before the operation of crimping and as said neck is located a suitable distance below the large end of the tapering 70 cork the internal crimping will grip and hold the cork securely therein, thus eliminating the use of the usual circular top piece which is glued or cemented to the top of the cork.

75 90 What I claim as my invention, is:—

1. In combination with a tapering bottle cork, a cover or shield comprising a hollow knurled knob, a crimped neck secured directly to the tapering cork a sufficient distance below its top to hold it securely therein, and a skirt with an internal groove formed from its lower edge and of sufficient internal diameter to pass freely over the enlarged top of neck of the bottle from which 100

it will be spaced entirely free from contact when the cork is tightly inserted within said neck.

2. In combination with a tapering bottle cork, a cover or shield comprising a hollow knurled knob provided with a hole in its top, a crimped neck secured directly to the tapering cork a sufficient distance below its

top to hold it securely therein, and a skirt with an internal groove formed from its lower edge and of sufficient internal diameter to pass freely over the enlarged neck of the bottle from which it will be spaced entirely free from contact when the cork is tightly inserted within said neck.

WALTER J. CARROLL.
